CONFECTION COATING MACHINE

Edwin J. Otken, New Brunswick, N. J., assignor
to Good Humor Corporation, Brooklyn, N. Y.,
a corporation of New York

Application May 13, 1949, Serial No. 93,110

4 Claims. (Cl. 107—1)

1 This invention relates to the art of coating machines for confections, and particularly involves a construction having great advantages over that shown in the machine of my co-pending application for patent Serial No. 59,315, filed November 10, 1948.

The machine herein disclosed is designed especially for the coating of so-called ice cream confections carried by sticks, whereby to obtain greatly increased efficiency of the machine, enabling material reduction of the time required for each coating operation, and reducing the power consumption required for operation of the machine, as well as having other advantages which will appear more fully hereinafter.

For a full understanding of my present machine I note that in the machine of my previous application above identified there is employed a rotatable drum having flights on the inner peripheral wall thereof for elevating and spilling down the coating material which usually consists of granular nuts, coconut, or the like, that is required to be adhesively applied to each of the confections treated in the machine. In my prior machine the confections are supported in a holder or rack of a conventional type utilized long heretofore, which rack is mounted on the drum so as to rotate therewith, after the confections have been engaged with the rack and held thereby. In the operation of said prior machine the drum is started into rotation for each coating operation, from a stopped or stationary position, by supplying current to a suitable motor which drives the drum. The confections supported in their holder are carried by and rotated simultaneously with the drum, and the coating operation is effected by the turning of the drum and the confections disposed therein as a unit, with the confections disposed in the path of the down-falling coating materials handled by the drum. When the drum has turned a number of revolutions according to my previous machine, means are provided to stop the same to enable the removal of the confections from their mounted connected relation to the drum after the coating operation has been completed. Necessarily, since the confections are rotated with the drum their rotation is relatively slow and the coating operation on this account involves a certain required number of rotations of the drum because the latter has to attain sufficient speed to properly elevate and spill downwardly in a continuous flow coating materials that fall upon the confections as the latter revolve with the drum. Again, in the operation

of my previous machine, the drum must be brought to a stop suddenly in order that the coating materials will not pile up and become applied to the confections in a non-uniform thickness or manner, the application being obtained by reason of the fact that the confection bodies are coated with an adhesive dip prior to their introduction into the drum in connected relation to rotate with the latter. For the sudden stoppage of the drum, therefore, there was heretofore employed certain brake mechanism to achieve the sudden stoppage action by which the surplus coating material was thrown off the confection bodies at the termination of the coating operation. The starting and stopping actions of the drum necessarily are time-consuming operations, and the machine hereinafter disclosed eliminates this phase of action of my machine of my prior application.

2 According to the specific construction of the machine as herein described, it is contemplated that the coating drum, once started into operation, shall be continued in constant rotation during the entire period when the machine is in use. The rotation of the drum is effected at a relatively high and uniform speed so as to produce in this manner a continuous turbulent shower of the coating material such as granulated nut meats, etc. at all times to be applied to confection bodies. In the further carrying out of my present improved construction of machine, I employ a stationary supporting frame at one side of the drum adjacent to the confection introducing opening of the latter, and I provide upon said frame a carrier rotatable independently of the drum for supporting the holder or rack by which the confections are held within the drum during the coating operation. Under these conditions the confection carrier is adapted to be operated entirely independently of the drum so that it may be properly manipulated to be rotated, likewise independently of the drum, during the continuous rotation of the latter, and in a direction opposite to the rotation of the drum, to more effectively obtain the necessary application of the coating material to all sides of the confection. Moreover, since the drum is continuously rotating, producing the continuous turbulent shower of the nuts therein at all times, I find that this action on the coating material enables the quick mounting of the confection rack or holder upon the rotary carrier whereby to introduce the confection bodies into the drum, and that by approximately a single turn or revolution of the rack supported confection bodies, the

coating operation may be fully completed. This action is distinguished from the operation of my previous machine, wherein the rotation of the confections was locked up with the rotation of the drum and was a considerably slower rotation dependent upon and corresponding with the rotation of said drum.

Since in the operation of my present improved machine to be hereinafter set forth, the stoppage of the drum for every coating operation, previously necessary in order to mount the confections on the drum to turn therewith, is no longer needed, time of the coating operation is greatly reduced, the wear and tear, incident to stopping and starting the drum, upon the electrical instrumentalities associated therewith, is entirely eliminated, including the wear and tear upon certain brake parts heretofore utilized for compelling the quick stopping action of the drum for reasons previously stated in respect to the former type of machine to which I have referred as embodied in my copending application, said brake parts no longer being used.

In addition to the foregoing, my improved machine as indicated above employs a much lower power consumption than my previous machine in view of the fact that less electric current is necessary to maintain the drum rotating at a uniform speed than is required for intermittently bringing the drum to the necessary speed for each coating operation, wherefore a motor of reduced horse power may be employed in my improved construction.

Again in the improved machine hereinafter set forth, certain labor operations are dispensed with in that it is unnecessary for the operator to start the machine each time a coating operation has to be performed and the labor of handling the confections and supervising the heretofore complicated operations of the former type machine is greatly reduced.

The result of actual commercial operation of the improved machine set forth herein is to increase the number of confections coated in a predetermined period of time to an extent of more than 100 per cent, so that the machine will afford a production of coated confections greater than possibly obtainable by the employment of the machines of the construction of my previous application for patent, aside from the incidental advantages mentioned above as regards the decrease in power consumption or current cost for operating the motor of the machine, and the general reduction in the wear and tear on the parts of the machine also previously referred to, the last involving, of course, a maintenance expense which it is desirable to avoid.

While in my present described machine the operation of rotating the confection bodies independently of the drum is converted into manual operation, the efficiency of the machine is in no way hampered by reason of the foregoing. In fact, since the operator is always required to lift the rack containing the confection bodies to be coated, and place the same so that the confection bodies are in the path of the down-pouring coating material within the drum, such operation is practically combined with that of mounting the confections on the separately rotatable carrier located at one side of the drum, thus quickly imparting to the confections substantially a single rotation in an opposite direction to the rotation of the drum, and quickly removing the holder or rack with the supported confection bodies coated completely, all involv-

ing practically a momentary action or operation affording the highly efficient complete functioning of the machine hereof for the reasons hereinbefore set forth.

In the improved machine herein disclosed, means is provided in the form of a shield or chute for causing coating material ejected from the drum during operation thereof to flow back into the drum. I also provide a novel construction of the confection carrier which permits it to be readily demounted from the stationary circular track upon which the carrier is normally rotatably mounted.

A preferred embodiment of a machine comprising the novel features of my invention is illustrated in the accompanying drawings, in which:

Figure 1 is a front elevation of the machine, looking toward the confection introducing opening of the drum and bringing out the mounting of the rotatable confection holding bracket or carrier and the supporting means therefor.

Figure 2 is a side elevation of my machine, with the drum shown in section and illustrating the manner of supporting the confection holder or rack on the rotatable bracket and guide wheel assembly, otherwise called a carrier, the flights on the inner peripheral wall of the drum being shown along with other parts of the machine, either directly carried by or associated with the drum, including the annular shield stationary adjacent to the opening of the drum, on which shield the carrier is rotatably supported.

Figure 3 is a front elevational view of the rotatable bracket assembly or confection carrier alone.

Figure 4 is a view inside elevation of the structure shown in Figure 3.

Figure 5 is an enlarged front elevational view of the combined shield and track member on which the rotatable carrier is supported.

Figure 6 is a sectional view taken about on the line 6-6 of Figure 5, looking in the direction of the arrows.

A machine embodying my invention includes generally a stand which may be comprised of any suitable fabricated structure, including vertical legs 1, horizontal bars 2 extending in one direction between the legs 1, other horizontal bar means 3 extending in a transverse direction to the bars 2, substantially vertical braces 4 extending upwardly from the front legs 1, and forwardly and upwardly inclined braces 5 leading from the rear legs 1 upwardly and forwardly so as to cross the front legs 1 so that beyond the latter the braces 5 are rigidly connected to the upper ends of the braces 4.

The top 6 of the stand is adapted to support any conventional type of motor 7, the driving shaft of which is connected to and supports partly the rotatable drum 8 which is circular in form and the outer periphery of which is additionally supported to rotate on rollers 10 supported by the horizontal bars 2 which extend from the front to the rear portions of the stand.

To facilitate the cleansing of the apparatus and compliance with sanitary regulations regarding machines for processing food products, the drum 8 is made of sectional construction in that the body of the drum includes the peripheral wall and annular front wall 8a formed with a large opening 8b therein, while the rear end of the drum is made up of a plate 9 detachably secured to a flange extending radially from the rear end of the peripheral wall of the drum, by

means of a plurality of screw bolts 9a. The motor shaft 11 enters a bearing member 12 on the outer face of the detachable rear end or plate 9 of the drum, and the shaft is fixed to the bearing member 12 by any suitable means desirably employed for the purpose.

On the inner side of the peripheral wall of the drum 8 are secured a plurality of blades or flights 13 disposed at intervals over such periphery, these blades being adapted to engage the granular coating material emplaced in the drum 8 preliminary to putting my machine in operation. Adjacent to the opening 8b, is mounted a unit which comprises a combined shield and chute 14 at the outer end of which is located a track 15 in the form of a flat plate attached to the adjacent peripheral edge of said shield 14. The shield 14 is of a construction such as to really provide a downwardly and inwardly inclined annular chute, of very large diameter, and slightly less than the diameter of the opening 8b in the drum. Thus any granular material which may be ejected from the drum through the opening 8b during the coating operation while the drum is elevating and spilling downwardly the coating material therein will flow back into the drum.

As seen best in Figures 1 to 4 of the drawings, the shield or chute 14 with its combined track member 15 is supported by means of horizontal members or arms 16 which are mounted on and rigidly attached to the upper ends of the inclined braces 5 at opposite sides of the machine. The inner ends of the arms 16 are welded or otherwise attached to the outer face of the track member or ring member 15 on the shield 14. The arms 16 are bolted at 17 to the outer sections 16a thereof that are attached to the braces 5. Thus, when it is desired to take the machine apart, as for cleansing operation, it is only necessary to remove the bolts 17 and the shield 14 and its track 15 as a unit may be removed from the stand along with a rotatable carrier supported upon this said unit, which will now be described.

The rotatable carrier above referred to is designed to support the confections which are to be coated. These confections are of the type, as primarily intended for use with my coating machine, wherein the confection bodies as seen in Figure 2 and designated 18, are carried on sticks 19. Such confections are generally known as stick confections, and they are handled in the ice cream factory after the sticks are frozen into the confection bodies by means of what is known as a stick holder or rack. This rack, in my drawings, is designated 20, and is of the type which is shown by Anderson Patent No. 2,232,196 issued February 18, 1941. Confection holding racks or holders of the type referred to have been used for many years prior to my invention in ice cream factories manufacturing stick confections, and I do not make any claim for the said rack or holder as a part of my invention. The confection holder or rack 20 is of a type in which the handles or sticks of the confection are secured before the freezing of the latter. The confection holder 20 is inserted in and supported by the combined shield and track 14-15. It will be observed from Figures 3 and 4 that the rack carrier consists of an approximately rectangular frame 21 provided with an opening 22 therein of rectangular shape and of a size such as to readily receive the rectangular shaped stick confection holder 20. The stick confection holder 20 is mounted upon the carrier 21 by simply in-

troducing the frame of the confection holder 20 into a frame member 23 extending inwardly from the opening 22 of the carrier frame 21 and against the inner sides of which frame the sides of the frame of the holder 20 rest, after the manner seen in Figure 2 wherein the stick confection holder or rack is mounted in place on the carrier frame 21.

The carrier frame 21 is designed to rotate on the track member 15 of the shield and track unit, and for this purpose I employ a plurality of arms 24, 25, and 26 located at spaced points on the frame 21 and supporting on their outer ends the grooved rollers or wheels 27. The axes of the several wheels 27 are disposed upon the arc of a circle which is concentric with the opening through the ringlike track member 15 and grooved portions of the wheels 27 receive the inner peripheral edge of the track 15 so that the carrier 21 may be freely rotated upon the combined shield and track 14-15. The arm 26, carrying one of the wheels 27, is made somewhat longer than the arms 24 and 25 so that the wheel bearing portion of the arm 26 may be extended to provide a hand crank 28 adapted to be grasped by an operator to effect free rotation of the carrier 21 relatively to the track 15 supporting the same. The roller 27 on the arm 26 is prevented from detachment from the arm by any suitable means, and the rollers 27 on the arm 24 and 25 are also held in place against detachment from the arms which support the same.

For the convenience of the operator, who usually stands in front of the machine adjacent to the drum 8, one of the arm members 16a carries a switch unit having a motor starting button 29 and a motor stopping button 30.

The operation of my machine as above set forth will now be described.

Ice cream stick confections or the like, such as those designed to be coated as to the confection bodies by means of my machine, are usually made by employing molds, which mold the individual confection bodies in groups or sets of twenty-four each, the sticks or handles of each of the confection bodies being attached thereto by congelation. The confections are released from the mold in the ordinary manner by employing the stick rack or confection holder 20 of the type of the Anderson patent previously referred to, the twenty-four confections being lifted out of the mold and then manipulated.

The confection holder or rack 20 with handles or sticks of the confections of a group which is to be coated, clamped thereto by the action of the mechanical parts of the said holder 20, is used to lift the confections from the mold or composite mold unit in which they are made, and convey the confections to a bath which includes an adhesive dip. The confection bodies are then dipped or submerged in said bath momentarily, lifted therefrom, and are ready to be placed in the coating machine while the drum 8 of the latter is rotating, having previously been supplied with a considerable quantity of granular materials for coating purposes, such as nut meats, coconut, or the like. The operator having previously started the drum 8 of the machine into rotation by starting the motor 7, the machine is maintained with the drum in constant or continuous rotation for the whole period of the many coating operations that are to be performed on the various groups of confections placed in the carrier 21. The continuous rotation of the drum 8 produces a constant uniform shower of the

coating material from the upper portion of the drum, off of the flights 13, and down toward the central space within the drum. The operator now places the confection holder 20 in the carrier frame or unit 21 after the manner shown in Figure 1, so that the confection bodies as seen in Figure 2 are in the path of the down showering coating material. Thereupon, the operator, by grasping the handle 28, will impart to the carrier 21 a rotatable movement. If the drum is rotating counterclockwise, the carrier 21 with the confection holder 20 and the confections supported thereby will be revolved clockwise or against the stream of down-pouring coating materials. I have found in the commercial machine embodying the construction of my invention as set up herein that a single revolution of the carrier frame 21 and the supported confections, requiring less than two seconds of time, will accomplish the coating operation. Immediately upon completion of the rotating movement of the carrier 21 with the confections supported thereon, the operator will remove the holder 20 from the carrier 21, and thereupon the confections are ready to bag and store for sale.

It will be obvious that the construction of the shield 14 is such that any material falling on the upper peripheral portion of the same will be deflected inwardly toward the central vertical plane of the drum, and likewise any of the coating material that may be splattered onto the lower peripheral portion of said shield will be deflected into the then bottom portion of the drum as the latter continuously rotates. There will be no loss of material for use for coating purposes under the above conditions, and material used up may be replenished by simply charging the drum through the opening 22 of the carrier frame 21 while the latter remains stationary.

As fast as the operator can mount groups of confections supported by the holders 20 on the carrier 21, give the frame one rotation, and remove the same, the coating operations will be consecutively performed incident to the continuous rotation of the drum 8, in a manner that will be obvious.

The drum 8 does not have to be stopped in order to dispose the confections in the range of the falling shower of coating material handled in the drum because the carrier means 21 is always ready to receive a fresh group of confections supported on one of the holders 20 due to the mounting of the carrier 21 separately from the drum so as to operate independently of the latter.

As seen best in Figures 1 and 2, a drip pan 31 is supported on the forward ends of the forwardly and rearwardly extending horizontal bars 2 of the stand frame. This pan is customarily employed to catch any drippings of the adhesive dip substance that is applied to the confection bodies previous to their introduction into the drum of the machine for the coating operation.

On the inner face of the detachable closed end plate 9 for drum 8 there are provided deflector blades 32, which, during the rotation of the drum, tend to deflect the down-falling shower of coating material toward the inner end of the confection bodies 18 as seen in Figure 2, so as to ensure the coating of said end portions.

It will be apparent, by reason of the fact that the drum 8 in operation is driven at comparatively high speed and is maintained at such speed uniformly throughout the use of the machine in the various consecutive coating operations, that this enables the coating material to be projected

directly onto the confection bodies positioned for receiving same to become adhered thereto while precipitated against the said confection bodies in the form of a continuous turbulent shower. The foregoing operation has been found very advantageous as distinguished from that of my previous machine of my identified application wherein the relatively slow rotation of the drum enables the coating material to slide off the flights or blades and gravitate to a large extent at one side of the confection bodies instead of being projected directly against these bodies under all conditions of the rotative action of the drum in acting upon the said coating material. Under these conditions, of course, the confection bodies do not have to remain in the drum in the path of the coating material except for the very short time, approximately two seconds, incidental to the operation of the carrier making approximately a single revolution with the confection bodies supported thereon.

In order to enable demounting of the carrier of Figure 3 from the circular track 15 with the periphery of which the grooved wheels 27 normally interlocking engage for rotation of the carrier on said circular track, the carrier frame 21 is of a resilient construction whereby the opposite sides of the frame 21 are yieldable relative to one another. It will be noted that the arm 26 is connected to the frame 21 about midway between the ends of one of the longer sides of said frame, and, as above stated, the axes of the several wheels 27 are normally disposed upon the arc of a circle which is concentric with the opening 35 through the ring-like track member 15, so that the grooves of the rollers 27 will be normally interlocked with the inner periphery of the track 15 to run on said track for rotation of the carrier frame 21 relative thereto.

Because of the resilient construction of the carrier frame 21 enabling the sides thereof to yield out of normal position, when it is desired to demount the carrier frame 21 from the circular track 15, it is only necessary for the operator to grasp the handle 28 and apply pressure thereon radially inwardly of the track 15, causing the sides of the frame 21 to which the arm 26 is connected to yield inwardly in like manner sufficiently to permit disengagement of the wheel 27 carried by the arm 26 from its interlocked connection with the periphery of the track 15, whereupon the other wheel 27 may be released from interlocked connection with the track 15 for demounting the carrier from said track.

Having thus described my invention, what I claim as new and desire to secure by Letters Patent of the United States, is:

1. In a machine of the class described, in combination, a coating drum rotatable about a horizontal axis and provided at an end thereof with a confection introducing opening, a motor operatively connected to the drum for continuously rotating the same, means in the drum to engage coating material and elevate and spill the same downwardly within the drum, a stationary circular track mounted adjacent to the open end of the drum, a confection carrier comprising a frame, bearing means between said frame and the said track comprising wheels carried by the frame and having peripheral grooves receiving the track, a confection rack adapted to support confections and mounted in the frame to hold the confections in a position in the path of the down-spilling coating material, means to rotate the carrier on said track combined with a shield sur-

rounding the carrier and located between the carrier and the drum and extending downwardly into the opening of the drum to cause down-spilling coating material received thereon to flow to the bottom of the drum, and means connecting the track with said shield to support the track in position.

2. A machine as claimed in claim 1 combined with arms extending outwardly from the carrier frame and each having one of said wheels on its outer end, one of said arms being extended at its wheel end to provide a handle constituting manual means to rotate the carrier.

3. In a machine of the class described, in combination, a support, means on the support to elevate and spill coating material in a predetermined path of movement, a stationary circular track juxtaposed to said elevating means, a confection carrier comprising a frame adapted to receive a rack to support confections thereon in the path of the down-spilling coating material, arms connected to the frame and offstanding therefrom, a wheel rotatably mounted on the outer end of each arm, said wheels normally interlocking with said track to run thereon for rotation of the carrier on the track, the carrier frame being resilient to permit one of the arms to yield radially inwardly of the periphery of said track for disengaging therefrom the wheel carried by said latter arm for demounting the carrier from the track.

4. In a coating machine, in combination, a sup-

porting frame, a coating drum rotatable about a horizontal axis on the frame, and provided with a confection introducing opening at an end thereof, means in the drum carried thereby to engage, 5 elevate and spill downward coating material within the drum, a motor connected to rotate the drum, a circular track mounted adjacent the open end of the drum, a confection carrier frame, a confection holding rack mounted in the carrier frame, bearing means between the carrier frame and the track, and a stationary shield surrounding the carrier frame and extending into the drum through said opening, the bottom of the shield inclining downwardly toward the drum to cause material passing out of the drum opening to pass back into the drum.
